UNITED STATES PATENT OFFICE.

WILLIAM H. THOMPSON, OF NEW YORK, N. Y.

TIME STAMP.

Application filed October 25, 1921. Serial No. 510,231.

To all whom it may concern:

Be it known that I, WILLIAM H. THOMPSON, a citizen of the United States, and a resident of New York, county of New York, 5 and State of New York, have invented an Improvement in Time Stamps, of which the following description, in connection with the accompanying drawings, is a specification, like characters on the drawings representing 10 like parts.

This invention relates to time stamps and the object is to provide in a compact and efficiently operating structure a majority of the useful elements of such an article in individually desirable embodiments and also to 15 provide thereby an organized unit which may be readily associated with complementary elements of various types and kinds whether in the original manufacture of time 20 stamps or in the repair and rebuilding of them.

My invention will best be understood by reference to the following description of an illustrative embodiment thereof shown by 25 way of example in the accompanying drawings, wherein:

Fig. 1 is a side elevation of a printing mechanism for time stamps, the cooperating parts of a time stamp on which such a 30 mechanism might be used being indicated in dotted lines:

Fig. 2 is a plan view of the same on an enlarged scale;

Fig. 3 is a detail as seen from the bottom 35 of Fig. 2; and

Fig. 4 is a section on the line 4—4 of Fig. 2.

In accordance with my invention as disclosed in the present illustrative embodiment 40 I provide as a unitary and self-contained arrangement printing and recording mechanisms which may be connected with a conventional clock movement to provide a time stamp and herein the printing elements are 45 supported by a frame including side bars 7 connected by a central web 9 and supporting at their ends casings 11 in which are mounted reels for an inking ribbon 13 adapted to extend across the face of the types. The side 50 bars 7 and web 9 may conveniently be cast and the casings 11 are most readily formed from sections of pipe secured to the ends of the bars 7. Formed on or secured to the web 9 I have shown a die or printing element 55 15 representing a clock dial and with this may cooperate the annular die 17 providing

for the printing of an hour indication and the die 19 for the printing of a minute indication. These dies are swivelled in the web 9 and suitable means are provided for clutching 60 them to a clock movement to be turned thereby and I have here shown (see Fig. 1) a suitably formed spindle 21 carried by the die 17 and projecting downwardly beyond the bottom of the frame and a spindle 23 projecting 65 from the die 19. In cases where it is desired to have an indication of the meridian a shiftable die 25 (see Fig. 2) may be provided having a similar spindle 27 clutching with the meridian operating mechanism 70 usual in clock movements designed for use in time stamps. In the present instance this die 25 is adapted to print alternatively the letter A or the letter P and a stationary but removable type 29 is used to print the letter 75 M.

The spaces between the arms 7 of the frame on either side of the central web 9 are utilized to support other desired printing elements which are so arranged on 80 transverse axes extending between the side bars as to be disposed entirely above the lower faces of these bars as will presently be more fully explained. Referring to Fig. 2 of the drawings, I there show a drum 31 85 in which may be mounted suitable logotypes for printing, for example, such words as "Received", "Answered" and the like, which drum is adapted to be rotated by a suitably inscribed handle 33 projecting at 90 the side of the frame to bring one or another type uppermost for printing. A spring pressed stud 35 may cooperate with the sides of a polygonal element 37 on the drum for locking it in adjusted position. Also 95 disposed on a transverse or horizontal axis extending between the arms 7, as shown at the lower part of Fig. 2, are a number of type wheels, 41, 47, 51 and 57, which are utilized to print a date. Herein the number 100 of the day is printed by two wheels, 41 and 47, each printing a single digit, and thus these wheels may be made of small diameter and, turning on a transverse axis as set forth, may be arranged so that they are disposed, as best shown by Fig. 4, entirely 105 above the lower surface of the frame. These wheels are preferably arranged so that they may be shifted by handles disposed at the side of the frame. I have herein (see Fig. 110 4) shown a spindle 39 on which is mounted the tens printing wheel 41 and which may

be turned by the handle or knob 43 secured to the end of the spindle 39 at the exterior of a bar 7. Mounted to turn on the spindle 39 is the sleeve shaft 45 carrying the 5 units printing wheel 47 and adapted itself to be turned by the knob 49. The wheel or wheels 51 which print the minutes are mounted on a similar sleeve shaft 53 operated by knob 55 at the opposite side of the 10 frame. Obviously this principle might be extended but I have herein shown a year printing wheel 57 mounted to turn loosely about the sleeve shaft 45 and adjustable by hand when necessary. Suitable spacing 15 sleeves 59 may be utilized to assist in positioning the various wheels relatively to the bars 7 of the frame.

The wheels may be positioned by the usual ratchets with which cooperate pawls 61 (see 20 Fig. 3) pivoted adjacent the lower side of web 9 and which may be pressed home by the tongues or teeth of a comb-like spring 63 secured to the under side of that web.

25 As indicated in Fig. 2, the various handles are suitably inscribed to correspond with the types on the wheels.

As is best shown by Figs. 1 and 4, the frame on which the various printing elements are mounted and which carries inking mechanism, typified herein by the ribbon 13, presents at its under side a smooth surface from which project solely the spindles for operating the hour printing dies as distinguished from the types for printing the dates and other legends. The under surface of the drum 31 and of the various date printing wheels are above the level of the lower portions of the side bars 7, as clearly 30 shown by Fig. 4. The lower surface of the frame is thus adapted to be placed against a clock casing and to mate with any suitable smooth surface thereon with the spindles 21 and 23 projecting into such casing 40 for connection with a suitable clock movement. Thus, referring to Fig. 1, I have there shown the body of a time stamp of conventional form having a clock enclosing casing 65 and having a flat surface 67 around the margin of a suitable opening giving access to the clock movement. Opposing this casing is the platen 69. The flat under surface of the frame may be applied to such a surface 67 and secured in 50 position by screws passing through the openings 71 (see Fig. 2). The spindles 21 and 23 and if the meridian changing dial is used, which is possible only with clocks having a meridian actuating mechanism, 55 the spindle 27 will project through the opening in the casing into cooperation with the clock movement. Only the hour shifting dies, which necessarily have to be connected with a clock, need attention although provision is made for a printing of much other

data. The other printing types, however, are arranged in a small and compact form and in such manner that they do not interfere in any way with securing the printing mechanism as a whole in position on the 70 clock casing. This is true also in instances where the casing is itself designed to carry day printing or other printing elements as these may be conveniently removed or omitted and the printing types of the present device will take their place. 75

Having thus described the particular embodiment of my invention shown by way of example in the accompanying drawings in great detail, not for the purpose of defining the subject matter of invention but in order that the arrangement of parts illustrated might clearly be understood, the principles exemplified thereby which I claim as new and desire to secure by Letters Patent I shall 80 express in the following claims. 85

Claims—

1. A self-contained printing member for time stamps comprising a frame having means for supporting an inking ribbon with a portion extending over the face of the frame, date printing wheels carried by the frame, hour printing dies carried by the frame and having operating shafts, means for securing said member to a clock casing, 90 said member presenting an even surface to mate with the casing from which surface project solely the shafts for operating the hour printing dies. 95

2. As a unit for use in the construction of time stamps, a frame, reel casings at the ends thereof thereby to provide for training an inking ribbon over the face of the frame, hour printing dies carried by the frame, and shiftable type elements for printing other data also carried by the frame and comprising a pair of numbering wheels for printing the number of the day of the month, and means exterior to the frame for shifting said elements beneath the ribbon. 100 105

3. A type holder for time stamps comprising a frame having provision for training an inking ribbon thereover, a series of date printing wheels within the confines of the frame, hour printing types swivelled in the frame and having means for clutching to a conventional clock movement exterior to the frame. 110 115

4. A self-contained type carrying member for time stamps comprising a pair of side bars, ribbon casings at the end thereof, shiftable printing elements organized to turn on one or more axes extending transversely between such bars, handles at the sides of the bars for shifting such elements and hour printing types swivelled in the frame having shafts projecting therefrom for clutching to a clock movement. 120 125

5. A time stamp comprising a casing containing a clock movement, said casing hav- 130

ing a smooth margined aperture opening to said movement, a platen opposing said aperture and a frame fitted to and secured to the margins of said aperture, said frame carrying inking means and printing types disposed clear of the boundary of the frame which fits said margin and also carrying hour printing types and motion transmitting means for said types projecting through the aperture into engagement with the clock movement.

6. A self-contained printing member for

time stamps comprising a frame having side bars and a connecting web, reel casings mounted on the ends of said side bars, a journal extending between said bars and supporting numbering wheels for printing a date, said wheels being disposed above the lower surface of the frame, and hour printing types swivelled in the web and having 15 spindles depending from the frame.

In testimony whereof, I have signed my name to this specification.

WILLIAM H. THOMPSON.
